UNITED STATES PATENT OFFICE.

WESLEY C. CASSON, OF HIGHLAND PARK, MICHIGAN, ASSIGNOR TO GENERAL MOTORS CORPORATION, OF DETROIT, MICHIGAN, A CORPORATION OF DELAWARE.

PRESSED-STEEL RUNNING BOARD.

Application filed November 20, 1926. Serial No. 149,676.

This invention relates to motor vehicles and particularly to the construction of the running board thereof.

The object of the invention is to construct a metal running board of a minimum number of pressed sheet steel stampings and to apply a novel finishing strip for holding the usual mat. The running board proper comprises a subframe or understructure consisting of two similar stampings upon which rests the foot plate. This plate has flanged edges embracing the understructure and a marginal depression or indentation to receive a U-shaped finishing strip. The strip has pressed out tongues which enter slots formed in the depressed edge and is the means for securing the mat to the foot plate. The mat is held between the upper and lower arms of the finishing strip and is applied in a novel manner, i. e. by bending upwardly the exposed arm of the strip and rebending it downwardly onto the mat after the latter has been set in place.

In the drawing:

Figure 1 is a plan view of the running board with parts broken away to better illustrate the construction.

Figure 2 is a transverse section on line 2—2 of Figure 1.

Figure 3 is a detail showing the manner of applying the securing strip to hold the mat, the full line position indicating the strip before it is bent onto the mat and the dotted position after it is bent.

Figure 4 is a detail taken on the line 4—4 of Figure 2 showing the manner of attaching the reinforcing strip to the plate.

Figures 5 and 6 show modified forms of attaching means.

Referring to the drawing, 1 designates the running board as a whole. This board is composed of a subframe comprising two identical stampings 2 and 3 pressed from a single sheet of metal and spaced from each other so as to form a trough 4 between them. One side of these stampings is channel shaped and this channel presents upwardly and has its edges oppositely flanged as at 5 and 6. The bottom of the channel may be provided with openings 18 to make a lighter structure.

At their outer sides each stamping has the frame member 7 integrally joined to the channel at both ends as shown at 8 and at points 9 spaced a short distance from the ends. The

joint at 9 is at the bottom of the stamping 55 and is a substantially broad piece of metal 10 having an opening 11 for the reception of the usual bolt to secure the running board to the supporting braces. The edges 12 of the portion 10 are flanged inwardly for stiffening 60 purposes, and similarly the lower edge of the frame 7 is flanged inwardly as at 13.

A flat foot plate 14, having downturned marginal flanges 15 on its four sides, overlies the stampings 2 and 3 of the subframe and 65 these flanges 15 extend below and lie in intimate contact with the lateral frame members 7. The lower edges of the flanges 15 are rounded and inwardly flanged as at 19 for stiffening purposes and between the side and 70 rear flanges a space 20 is allowed. At the ends of the stampings 2 and 3, flanges 16 are provided for securing the stamping end to the end flange 15 of the plate 14.

The parts so far described may be secured 75 together by riveting welding, or by any other suitable means.

Overlying the foot plate 14 is a mat 17 which may be of any suitable material. This mat is shown as having a smooth surface but 80 obviously it may be corrugated, or otherwise roughened.

The plate 14 has a narrow depression 21 extending completely around its upper border and in this depression there is punched 85 a plurality of slots 22 the purpose of which will be later specified.

In order to hold the mat 17 on the plate 14, securing or finishing strips 23 are applied at the edges of the plate. These strips are of 90 U-shape, Figures 2 and 3, with the lower arm of the U slightly broader and resting in the depression 21. The strip 23 is of any suitable material, preferably aluminum, and has punched therefrom at suitable intervals 95 tongues 25, the adjacent tongues being bent in opposite directions as shown in dotted outline in Figure 1. The spacing of these tongues corresponds to the spacing of the slots 22 of the plate 14 and this tongue and 100 slot connection 25, 21 affords a means of securing the finishing strip to the plate 14 by bending the tongues under and against the lower side of the plate, Figures 2 and 4.

The upper arm 26 of the strip 23 is upwardly bent, Figure 3, to allow for the insertion of the mat 17, and then bent downwardly onto the mat edge as shown in full lines in

Figure 2 and by dotted outline in Figure 3 to hold the mat. The mat lies over the plate 14 and the lower arm 24 of the strip 23, the depth of the depression 21 being substantially 5 equal to the thickness of the arm 24. It will of course be understood that only the strips at one side and end need be bent to the angle shown in Figure 3. The upward bend at the other two edges need only be sufficient to 10 allow the mat to be slid into place.

In the modification in Figure 5 I show the finishing strip 23 secured by means of a rivet 27, having its head countersunk in the arm 24 as shown at 28 and passes through and 15 has its lower end upset against the under side of the plate 14.

In the modification of Figure 6 a bolt 29 having a nut 30, a spring washer 31 and a countersunk head 32 is used to hold the finishing strip onto the plate 14. This structure is analogous to that of Figure 5 the difference residing in the use of a bolt instead of a rivet.

I claim:

1. A running board for motor vehicles consisting of a subframe comprising a plurality of similar stampings, each stamping comprising a channel shaped portion and a lateral frame portion, said stampings having a trough between them, and a flanged plate 30 overlying said subframe.

2. A running board for motor vehicles consisting of a subframe composed of a plurality of similar stampings, each stamping comprising a channel shaped portion and a lateral 35 frame portion, said stampings having a longitudinal trough between them, a plate overlying said subframe, downturned flanges at

the edges of the plate, said flanges embracing the frame portion.

3. A running board for motor vehicles 40 consisting of a subframe composed of a plurality of similar stampings, each stamping comprising a channel shaped portion and a lateral frame portion, a joint intermediate the ends of the channel and frame portions said joint comprising a relatively broad metallic portion having a bolt opening for securing the running board to the vehicle.

4. In a running board, a stamped metal subframe, a plate, a depressed margin on said plate, flanges at the margin, said plate overlying and having its flanges embracing said subframe, and a finishing strip seated in said depression.

5. In a running board for automotive vehicles, a stamped metal subframe, a flanged plate overlying said subframe, said flanges embracing said subframe, a depressed margin on said plate, a mat overlying said plate, and a finishing strip seated in said margin 55 and securing said mat to said plate.

6. The invention of claim 5, said finishing strip comprising a U-shaped metallic member, one leg of the U resting on and secured at the depressed margin, the other leg extending over and folding down on the mat.

7. The invention of claim 5, said finishing strip comprising an originally L-shaped member having the base of the L seated on and secured at the depressed portion, and the leg of the L later bent over onto the mat.

In testimony whereof I affix my signature.

WESLEY C. CASSON.
